(57) **CLAIM**

The ornamental design for a bodily fluid drainage bag cover, as shown and described.

DESCRIPTION

FIG. 1 is a perspective view of a bodily fluid drainage bag cover;

FIG. 2 is a front plan view thereof;

FIG. 3 is a right side elevation view thereof, it being understood that a left side elevation view thereof is a mirror image of FIG. 3;

FIG. 4 is a top elevation view thereof;

FIG. 5 is a bottom elevation view thereof;

FIG. 6 is another perspective view thereof in which the bodily fluid drainage bag cover is attached to a bodily fluid drainage assembly and is in a lowered state; and,
FIG. 7 is another perspective view thereof in which the bodily fluid drainage bag cover is attached to a bodily fluid drainage assembly and is in a partially raised state.

The dash dot lines immediately adjacent the shaded areas represent the bounds of the claimed design. The dashed lines in the figures are directed to environment. None of the broken lines form part of the claimed design.
